US0D1079929S

(12) **United States Design Patent** (10) **Patent No.:** **US D1,079,929 S**
(45) **Date of Patent:** **** Jun. 17, 2025**

(54) **FAN BLADE**

- (71) Applicant: **Zhongshan Sanfan Electrical Appliance Co., Ltd**, Zhongshan (CN)
(72) Inventor: **Qingkun Guo**, Zhongshan (CN)
(73) Assignee: **ZHONGSHAN SANFAN ELECTRICAL APPLIANCE CO., LTD**, Zhongshan (CN)

(**) Term: **15 Years**

(21) Appl. No.: **29/818,375**

(22) Filed: **Dec. 8, 2021**

(30) **Foreign Application Priority Data**

- Aug. 26, 2021 (CN) 202130559087.7

CLAIM

The ornamental design for a fan blade as shown and described.

DESCRIPTION

FIG. 1 is a perspective view of a fan blade showing the new design;

FIG. 2 is a front view thereof;

FIG. 3 is a rear view thereof;

FIG. 4 is a side view thereof;

FIG. 5 is an opposing side view thereof;

FIG. 6 is a top view thereof;

FIG. 7 is a bottom view thereof; and,

FIG. 8 is a perspective view of the fan blade shown in an environment of use.

The broken lines shown herein are for illustrative purposes only and form no part of the claimed design.

1 Claim, 8 Drawing Sheets
